CLAIM

The ornamental design for a patterned heater pedestal with groove extensions as shown and described.

DESCRIPTION

FIG. 1 is a top perspective view of a patterned heater pedestal with groove extensions showing my new design; FIG. 2 is a bottom view thereof;

FIG. 3 is a front view thereof, the back view being the mirror image thereof;

FIG. 4 is a side view thereof, the opposite side view being the mirror image thereof;

FIG. 5 is a top plan view thereof;

FIG. 6 is a bottom plan view thereof;

FIG. 7 is an enlarged detail view of area 7 circumscribed in FIG. 1;

FIG. 8 is an enlarged detail view of area 8 circumscribed in FIG. 1; and,

FIG. 9 is an enlarged detail view of area 9 circumscribed in FIG. 8.

The broken lines depict portions of the patterned heater pedestal with groove extensions that form no part of the claim. The dash-dot-dash broken lines denote the boundaries of the detail areas and form no part of the claimed design.
